UNITED STATES PATENT OFFICE

2,228,340

REFRIGERATING APPARATUS

Clifford R. Carney, Miami, Fla., assignor to Nash-Kelvinator Corporation, Detroit, Mich., a corporation of Maryland

Application September 21, 1938, Serial No. 230,943

1 Claim. (Cl. 62—108.5)

The present invention relates to refrigerating apparatus and more particularly to freezing trays for use in connection with such apparatus.

It is an object of the present invention to pro-

5 vide an improved ice tray including a pair of removable grids which are also movable relatively to each other.

It is another object of the present invention to provide a tray with a grid assembly constructed 10 of two sections whereby the operation of a lever will progressively affect the sections to break the cubes frozen therein loose from the tray.

Another object of the present invention is to provide a structure that is economical of manufacture, durable in structure, highly efficient in 15 use, and one having a minimum number of parts.

The invention itself, however, both as to its organization and its method of operation together with additional objects and advantages 20 thereof, will best be understood from the following description of specific embodiments when read in conjunction with the accompanying drawing, in which:

Fig. 1 is a fragmentary cross-sectional view of 25 a refrigerator illustrating features of my invention;

Fig. 2 is a plan view of the invention;

Fig. 3 is a cross-sectional view taken substantially on line 3—3 of Fig. 2;

30 Fig. 4 is a cross-sectional view taken substantially on line 4—4 of Fig. 2;

Fig. 5 is a cross-sectional view taken substantially on line 5—5 of Fig. 3;

35 Fig. 6 is a cross-sectional view taken substantially on line 6—6 of Fig. 3.

In the drawing, I have shown a refrigerator 10 provided within its compartment 12 with an evaporator 14 having passages wherein is admitted volatile refrigerant for effecting and maintaining a proper temperature within the compartment. The refrigerant is withdrawn, condensed and returned to the evaporator by means of a suitable compressor and condenser apparatus (not shown). The evaporator has provisions for 15 the reception of trays 16 for freezing of the contents therein.

The tray 16 is subdivided into a plurality of small chambers 18 by a grid assembly composed of sections 21 and 22. The grid section 21 comprises a longitudinally extending wall 24 having affixed thereto laterally extending side walls 25. The grid section 22 is similarly formed of a longitudinally extending wall 29 having laterally extending walls 30. The walls 24 and 29 are set 55 spatially apart and parallel to each other with

their ends secured together by rivets 32 which are carried by wall 29 and project through slots 33 of wall 24 allowing for movement of each grid section relative to the other.

A handle or lever 35 is provided with an extension 36 projecting downwardly within the spatial distance formed between the parallel walls 24 and 29. Secured in, and extending outwardly from one side of the extension 36 is a stud 37 adapted for projecting through the inclined slot 39 formed in wall 29. A second stud 40 is fixedly secured above the stud 37 in the extension 36 to project outwardly from the opposite side to be journaled in the wall 24.

The slot 39 is so cut in the wall 29 as to be a chord for an arc that would be subtended by the stud 37 were it to travel freely about the axis of the journaled stud 40. By this arrangement and construction as the handle 35 is rocked upwardly on the axis of stud 40, the stud 37 20 will ride up the inclined or chordal slot 39 forcing the stud 40 to move outwardly. That is, by the perpendicular guidance of the rivet in slots 33 the stud 40 will force the grid assembly to move upwardly. The contents frozen within 25 this section will be by this vertical movement loosened and freed from its frozen bondage with the tray 16. Further rocking of the handle will bring the stud 37 to the end of slot 39, whereupon it becomes the pivoting axis for the handle 35 moving the stud 40 with its associated grid assembly 21 downwardly to again rest upon the tray's bottom. Continuing the swing of the handle 35 will shift the pivoting axis back to stud 40, forcing stud 37 in its arcuate travel about 30 stud 40 to carry the grid section 22 upwardly in a vertical movement also guided by the rivets 32 in slots 33, and thus effecting a similar release- 35 ment of the contents frozen in section 22 to be loosened and freed from the tray 16. The section 22 is returned to its normal or horizontal 40 position by the return travel of the handle 35.

To easily break the adhesion of the frozen cubes from the surfaces of the grids, the assembly is made of thin flexible stock allowing for the longitudinal walls 24 and 29 to be arcuately bent by movement of handle 35, thus expanding the dimensional width between side walls 25 or 30, as determined by direction of flexing walls 24 and 29, allowing the cubes to drop out. The spatial distance between the walls 24 and 29 will allow this flexing movement, with the ends of the walls secured together.

While I have described the preferred form of my invention I do not wish to limit myself to the 55

precise details as shown, but wish to avail myself of such variations and modifications as may come within the scope of the appended claim.

I claim:

- 5 In a freezing apparatus for liquids, the combination of a tray for making ice cubes, a grid including two sections within the tray and adapted to form a plurality of ice cube molds, and

a single handle associated with said sections and being arranged to simultaneously apply a downward force against one section and an upward force against the other section and later an upward force against the first named section and a downward force against the second named section. 5

CLIFFORD R. CARNEY.
